UNITED STATES PATENT OFFICE

103,002

DESIGN FOR A FINGER RING

Frank Carolan and Robert R. Rhoerbaugh,
Casper, Wyo.

Application October 6, 1936, Serial No. 65,186

Term of patent 7 years

To all whom it may concern:

Be it known that we, Frank Carolan and Robert R. Rhoerbaugh, citizens of the United States, residing at Casper, in the county of Natrona and the State of Wyoming, have invented a new, original, and ornamental Design for finger rings, of which the following is a specification, reference being had to the accompanying drawing, forming part thereof.

The figure is a perspective view of a finger ring, showing our new design.

We claim:

The ornamental design for a finger ring, as shown.

ROBERT R. RHOERBAUGH.
FRANK CAROLAN.
